DESIGN FOR A BOTTLE

Stephen L. Nordlinger, Hawthorne, N. Y., assignor to Conti Products Corp., New York, N. Y., a corporation of New York

Application December 22, 1933, Serial No. 50,186

Term of patent 14 years

To all whom it may concern:

Be it known that I, STEPHEN L. NORDLINGER, a citizen of the United States, residing at and whose postoffice address is Hawthorne, in the county of Westchester and State of New York, have invented a new, original, and ornamental Design for a Bottle, of which the following is a specification, reference being had to the accompanying drawing, forming part thereof.

I claim:

The ornamental design for a bottle, as shown.
STEPHEN L. NORDLINGER.
